The ornamental design for a set of female members for snap
buttons on tape, as shown and described.

(22) Filed: **Jun. 14, 2001**

DESCRIPTION

Dec. 15, 2000 (JP) 2000-035868

FIG. 1 is a front view of a set of female members for snap
buttons on tape according to the present invention;

(51) LOC (7) Cl. **02-07**

FIG. 2 is a side plan view of FIG. 1;

(52) U.S. Cl. **D11/220**

FIG. 3 is a left side view of FIG. 1;

(58) Field of Search D11/200, 220;

FIG. 4 is a right side view of FIG. 1;

24/693, 662-681, 114.6, 114.4, 688, 695,

FIG. 5 is a cross-sectional view taken on line 5—5 of FIG.

DIG. 29

4; and,

FIG. 6 is a cross-sectional view, similar to FIG. 5, showing
the article in use.

The broken lines in FIG. 6 are for illustrative purposes only
and form no part of the claimed design.
